UNITED STATES PATENT OFFICE.

PAUL DUNLAP, OF RICHMOND, CALIFORNIA.

COMBINED MUFFLER AND VAPORIZER.

Application filed July 11, 1921. Serial No. 483,988.

To all whom it may concern:

Be it known that I, PAUL DUNLAP, a citizen of the United States, residing at Richmond, in the county of Contra Costa and State of California, have invented certain new and useful Improvements in a Combined Muffler and Vaporizer; and I do hereby declare the following to be a full, clear, and exact description of the invention, such as will enable others skilled in the art to which it appertains to make and use the same.

The invention relates to an explosive engine adjunct whereby the exhaust is muffled and utilized as means to facilitate the vaporization of crude oil and like low grade fuel whereby the same may be advantageously used as gas producing means in the operation of the engine.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a side view of a combined muffler and vaporizer constructed in accordance with and embodying the essential features of the invention,

Figure 2 is a vertical central longitudinal section thereof,

Figure 3 is a transverse section on the line $x-x$ of Figure 2 looking in the direction of the arrows, and

Figure 4 is a section on the line $y-y$ of Figure 2.

Corresponding and like parts are referred to in the following description and designated in the several views of the drawings by like reference characters.

The device comprises a drum 1 such as usually provided for the exhaust of internal combustion engines. The receiving end of the drum 1 is made tapering as indicated at 2 and the exhaust pipe 3 connects centrally therewith. The rear end of the drum 1 is flat and provided centrally with an outlet 4 with which the exhaust pipe connects. A drum 5 corresponding in outline to the drum 1 is disposed concentrically within the latter and spaced therefrom. The pointed end

6 of the inner drum 5 is disposed opposite the center of the exhaust pipe 3 to uniformly deflect the gases in their passage through the space 7 formed between the two drums. 60 Baffles 8 project inwardly from the wall of the outer drum 1 and other baffles 9 project outwardly from the drum 5 and are disposed intermediate the faces of the baffles 8 whereby to retard the passage of the gases 65 and compel them to take a tortuous or continuous path. The baffles are rearwardly inclined so as to offer a minimum resistance to the flow of the gases while effecting a deflection thereof. The baffles 8 and 9 consist of rings which are attached at one edge to the respective drums.

A pipe 10 connects with the upper portion of the inner drum 5 near the rear end thereof and extends across the space 7 and 75 through the drum 1. The receiving end of the pipe 10 constitutes a mixing chamber for the air and fuel and is provided at its inner end with a valve seat 11 upon which closes a valve 12. The stem 13 of the valve 80 12 engages the inner end of a lever 14 pivoted to a side of the pipe 10 and extending therethrough. The outer end of the lever 14 is adapted to be connected with a controlling element (not shown) in a manner well 85 understood.

An air pipe 15 extends vertically through the rear portions of the drums 1 and 5 and its upper end connects with the valve seat 11. The lower end of the air pipe 15 terminates a short distance below the drum 1 and is provided with an externally threaded flange 16 with which an air strainer 22 is detachably connected. The stem 13 of the valve 12 depends from the latter and passes 90 through the air pipe 15 and receives an expandable helical spring 17 which assists materially in the seating of the valve 12.

A fuel pipe 18 extends through the rear portion of the drums 1 and 5 and terminates in a spray nozzle 19 within the lower rear portion of the drum 5, the fuel pipe 18 is provided in its length with a valve 20 which is connected with the stem 13 by means of a rod 21 or like part whereby movement of the stem 13 to unseat the valve 12 also operates to open the valve 20 to permit of an increased supply of fuel to the drum 5.

The air strainer 22 comprises an internally threaded collar 22' to make a screw-thread engagement with the flange 16 and a wire frame 23 having its element attached to the

collar 22'. A wire gauze 24 envelopes the frame 23 and is supported thereby and is retained in position by means of an elastic or spring band 25 engaging the upper gathered end of the fabric 24 and the collar 22'. The wire gauze 24 or similar material excludes dust and prevents the same entering the air pipe 15 and passing to the engine. The inner wall of the pipe 10 is rifled or 10 provided with a spiral plate 26 whereby to impart a whirling motion to the air and gas to cause a thorough admixture thereof and assist materially in breaking up particles of the fuel to obtain the maximum vaporization 15 thereof.

A baffle 27 is disposed within the drum 5 and is arranged horizontally and secured at its rear end to the rear end of the drum 5 and at its longitudinal edges to the inner 20 wall of the drum 5 at diametrically opposite points. The baffle 27 consists of a plate and its forward end is spaced from the front end of the drum 5. The space in the lower portion of the drum 5 below the baffle 27 is 25 filled with loose elements 29 which preferably consists of wire. The spaces between the element 29 constitute in effect innumerable minute passages for the circulation of the fuel whereby affording ample opportunity 30 for proper heating of the same to insure vaporization thereof when escaping into the mixing chamber at the receiving end of the pipe 10.

When the device is in operation the fuel 35 is supplied to the drum 5 by means of the pipe 18 and is sprayed by the nozzle 19 into the rear portion of the space below the baffle 27 and is heated in its passage through the spaces formed between the elements 29 and 40 is further heated in its travel through the upper portion of the drum 5 above the baffle 27 and escapes into the pipe 10 through outlets 11^a at the seat 11 which are adapted to be closed by means of the valve 12. When the 45 valve 12 is unseated the suction created in the pipe 10 by means of the engine draws air through the pipe 15 and fuel from the drum 5. The fuel in a vaporized state meets the air at the seat 11 which coincides with the 50 entrance of the opening chamber and the mixture of air and gas passes through the pipe to the engine in a manner well understood. A whirling movement is imparted to the gaseous mixture in its travel through 55 the pipe 10 by reason of the whirling or spiral plate 26 thereby insuring a thorough agitation of the mixture and a breaking up of the particles of fuel prior to the entrance of the gas into the engine.

60 While the invention is designed chiefly for low grade oil it is equally clear that liquid fuel of any grade and nature may be utilized, the more volatile the fuel the more easily will the same vaporize.

65 The air strainer is detachably connected

to the air pipe 15 preferably by screw threads as shown, however, the connection may be made in any way so long as the strainer is removable and secure when in position. The gauze 24 may be of any fabric—textile or otherwise, so long as the mesh is sufficiently fine to exclude dust without materially impeding the flow of air 70

Having thus described the invention, what I claim is:—

1. A combined muffler and vaporizer comprising spaced outer and inner drums, means for circulating the exhaust from the engine through the space between the two drums, means for supplying fuel to the inner drum and an air pipe extending through the two drums and across the space formed between them, said pipe having an opening communication with the inner drum to receive the vaporized fuel therefrom, a valve for controlling the passage of air and vaporized fuel through said pipe and into the mixing chamber connected therewith, and baffles in the space formed between the two drums to retard the passage of the exhaust and cause the same to make a tortuous or continuous path. 80

2. A combined muffler and vaporizer comprising spaced outer and inner drums, means for circulating the exhaust from the engine through the space between the two drums, means for supplying fuel to the inner drum and an air pipe extending through the two drums and across the space formed between them, said pipe having an opening communication with the inner drum to receive the vaporized fuel therefrom, a valve for controlling the passage of air and vaporized fuel through said pipe and into the mixing chamber connected therewith, and baffling means within the inner drum to cause the fuel to take a tortuous passage in its travel therethrough. 90

3. A combined muffler and vaporizer comprising spaced outer and inner drums, means for circulating the exhaust from the engine through the space between the two drums, means for supplying fuel to the inner drum and an air pipe extending through the two drums and across the space formed between them, said pipe having an opening communication with the inner drum to receive the vaporized fuel therefrom, and a valve for controlling the passage of air and vaporized fuel through said pipe and into the mixing chamber connected therewith, a baffle plate in the inner drum dividing the same into upper and lower spaces which are in communication at their forward ends and loose elements in the lower space providing minute passages for the flow of the fuel and an extending heating surface therefor. 110

4. A combined muffler and vaporizer comprising spaced outer and inner drums, means for circulating the exhaust from the engine 120

through the space between the two drums, means for supplying fuel to the inner drum and an air pipe extending through the two drums and across the space formed between them, said pipe having an opening communication with the inner drum to receive the vaporized fuel therefrom, a valve for controlling the passage of air and vaporized fuel through said pipe and into the mixing chamber connected therewith, and an air screen applied to the receiving end of said air pipe for filtering the air.

5. A combined muffler and vaporizer comprising spaced outer and inner drums, means for circulating the exhaust from the engine through the space between the two drums, means for supplying fuel to the inner drum

10 and an air pipe extending through the two drums and across the space formed between them, said pipe having an opening communication with the inner drum to receive the vaporized fuel therefrom, a valve for controlling the passage of air and vaporized fuel through said pipe and into the mixing chamber connected therewith, and a fuel regulating valve operatively connected with the aforementioned valve to insure simultaneous operation of both valves.
